LOADING MACHINE

Einar M. Arentzen, Charleroi, Pa., assignor, by
mesne assignments, to Joy Manufacturing
Company, Franklin, Pa., a corporation

Application August 20, 1941, Serial No. 407,525

8 Claims. (Cl. 198—10)

This invention relates to improvements in loading machines particularly adapted for gathering and loading coal at the working face of a mine.

Among the objects of my invention is to provide a simple and efficient machine of the character described, including a truck mounted on pneumatic tires for self-propulsion and controlled for steering in all four wheels, and wherein a new and improved form of gathering mechanism is employed affording a wider spread of gathering action at the front end of the machine than has been possible with machines of this general type. A further object of the invention is to provide an improved construction and mounting for the material-discharge conveyor at the rear of the machine to facilitate the lateral swinging movement thereof. Other objects of the invention will appear from time to time as the following description proceeds.

The invention may best be understood by reference to the accompanying drawings, in which

Figure 1 is a view in side elevation of a loading machine constructed in accordance with my invention;

Figure 2 is a plan view of the machine shown in Figure 1;

Figure 3 is a fragmentary plan view of the central part of the machine chassis, with the longitudinal conveyor removed to show details of the propelling and steering mechanism;

Figure 4 is a side view of the chassis parts shown in Figure 3, with the wheels on the near side removed;

Figure 5 is an enlarged transverse section taken along the front axle of the machine and looking rearwardly thereof;

Figure 6 is a transverse section taken along the rear axle of the machine and looking rearwardly thereof;

Figure 7 is an enlarged detail section of the gathering head taken generally on line 7—7 of Figure 2;

Figure 8 is a detail section of the gathering head taken on line 8—8 of Figure 2;

Figure 9 is a transverse section taken on line 9—9 of Figure 7;

Figure 10 is an enlarged fragmentary detail view showing the mat conveyor structure;

Figure 11 is a side view of the mat conveyor structure shown in Figure 10;

Figure 12 is a detail section taken through the front end of the gathering head on the same section line as Figure 8, but drawn to a greatly enlarged scale;

Figure 13 is an enlarged fragmentary detail

view showing the chain drive connections for the gathering arms and mat conveyor;

Figure 14 is a detail horizontal section showing the detachable mounting for the transmission casing;

Figure 15 is an enlarged fragmentary plan view showing details of the discharge conveyor in the zone of its articulated connection; with the rear conveyor section swung toward one side of the machine; and

Figure 16 is a vertical section taken longitudinally of the machine, showing details of the articulated connection of the discharge conveyor and the fluid-operated elevating mechanism therefor.

In the embodiment of the invention illustrated in the drawings, the loading machine consists generally of a wheel-supported main frame 10 having a gathering head indicated at 11 pivotally connected on a transverse axis at the front end thereof and having an elevating and discharge conveyor 12 extending rearwardly from the gathering head and projecting beyond the rear end of the main frame for discharge into mine cars or the like. In the preferred form shown, the wheeled supports consist of front and rear pairs of pneumatic tired wheels 13, 13 and 14, 14, respectively. Both front and rear wheels are power driven, and are also arranged for steering the vehicle so as to facilitate the maneuvering of the latter in limited spaces such as are commonly encountered in coal mines.

The gathering or loading head 11 includes a pair of gathering devices 15, 15 having a gathering motion somewhat similar to that heretofore employed in familiar Joy type loading machines, but as will presently be described in detail, said arms cooperate in a novel manner with an endless mat type conveyor 16 extending to the front edge of the gathering head so as to provide an improved gathering action covering a wider gathering area than has heretofore been possible with gathering heads of similar character.

Referring now to details of the machine illustrated in the drawings, the main frame 10 consists of a pair of side frame members 20, 20 herein consisting of upright plates extending lengthwise of the vehicle and supported on front and rear drop-axle structures indicated at 21 and 22, respectively, designed to give an especially low-slung body.

In the form shown herein, said drop-axle structures and the steered wheel mountings and drive means associated therewith, are similar to those employed in the co-pending applications of

Arthur L. Lee, bearing Serial Nos. 383,329 and 383,331, both filed March 14, 1941. The front wheels 13, 13 are pivoted for steering on universal drive mountings indicated generally at 23, 23 in Figure 3, which mountings are driven through horizontal shafts 24 journaled in upright drive gear housings 25, 25 mounted on the opposite ends of an axle member 26 (see Figure 5). Said axle member is in the form of a relatively flat metal slab and is arranged for equalizing action wherein the axle member 26 extends through an elongated housing 31 which is rockably mounted on a pivot pin 32 mounted centrally of the frame between a pair of transverse supporting plates 33, 33 connected between the side frame members 20, 20, as shown in Figure 5. The pivot pin 32 engages the upper face of the axle 26 at its center point, so as to permit limited lateral rocking movement of the axle structure, thereby providing in effect a three-point suspension of the main frame. It will also be noted that the axle 26 is loosely fitted within the housing 31 so as to permit limited flexing of said axle member under varying loads.

The rear wheels 14, 14 are also mounted for steering on upright universal drive mountings 27, 27, which mountings are driven through horizontal shafts 28, 28 journaled in upright drive gear housings 29, 29 at opposite ends of a flat drop-axle member 30. The latter member has the side frame members 20, 20 supported thereon adjacent its ends, so as to permit limited flexing of said axle member under varying loads, as described and claimed in the Lee applications previously referred to. Other details of the drive and steering connections for the front and rear wheels 13, 13 and 14, 14 will presently be described in detail.

The gathering or loading head 11 is disposed as usual at the front end of the vehicle and includes a frame 17 having two upright, laterally spaced side plates 34, 34, each having an upwardly and rearwardly inclined gathering plate 35 connected along its upper edge and extending outwardly therefrom. Said loading head is pivotally connected to the front ends of the main frame members 20, 20 by rearward extensions 34a, 34a on side plates 34, 34, as shown in Figure 8. Pivotal adjustment of the gathering head is controlled by a pair of fluid motor devices, such as hydraulic cylinders 18, 18, mounted on opposite sides of the main frame members 20, 20 and having their pistons 18a, 18a pivotally connected to upstanding wings 34b, 34b at the rear ends of the gathering plates 35, 35. Hydraulic pressure may be supplied as usual to the cylinders 18, 18 under control of suitable valves (not shown).

The mat conveyer 16 includes an endless belt-like steel conveyer structure disposed between the side frame plates 34, 34, and having its upper carrying surface substantially in the same plane as the gathering plates 35, 35. As herein shown, said conveyer structure is made up of a plurality of chain-like links 36, 36, each bent in U-shape to form a closed end 36a and open ends 36b. Said links are pivotally connected by transverse pivot rods 37, 37 passing through opposite ends of said links, as shown in Figures 10, 11 and 12. Spacer collars 38, 38 are mounted on the rods 37 between the open ends 36b of each link. Single links 39, similar to conventional chain links, are connected along opposite sides of the conveyer structure. The pivot rods 37 have heads 37a, 37a suitably formed at opposite ends thereof to hold the mat structure together.

The upper reach of the mat conveyer 16 is supported for movement along a deck plate 40 rigidly secured between the upright side plates 34, 34. Said mat passes over a transverse bearing bar 41 of relatively small diameter secured between the side plates 34, 34 close to the front of the gathering head, so that the mat presents a relatively sharp, wedge-like digging edge which may be projected into direct operative engagement beneath the material being loaded. In the preferred arrangement shown in Figure 2, the U-shaped links 36 are arranged so that their closed transverse end portions 36a are in following position when the conveyer is in operation. Thus as the individual links 36 move forwardly and upwardly around the bearing bar 41, their closed ends 36a present an exposed transverse edge to assist in the digging and gathering action of the conveyer.

The rear end of the mat conveyer 16 passes over an idler roller 44 disposed at the rear end of the supporting plate 40, and adjacent the rear limits of the gathering plates 35. From thence the lower reach of said conveyer passes downwardly and forwardly over an idler take-up roller 46 and a plurality of drive sprockets 47 keyed on a sprocket sleeve 48, as shown in Figure 8. Said drive sprockets have suitable driving engagement with the spacer collars 38 between the individual links 36, as shown in Figure 9. The sprocket sleeve 48 has shafts 49 and 49a fixed in opposite ends, suitably journaled in gear housings 42, 42 rigidly connected beneath the gathering plates 35, 35, outside of the upright side frame plates 34, 34. The shafts 49 and 49a also have bevel gears 50, 50 at opposite ends thereof, having driving connection with the gathering devices 15, 15, as will presently be described.

The conveyer 16 is driven by a motor 52 mounted centrally of the main frame through the following drive connections:

The motor 52 has an armature shaft 51 connected by coupling shaft 53 to reduction gears 54 and clutch 54a in a transmission casing 55. Said reduction gears and clutch may be of any suitable form, for driving a shaft 56 extending through one end of the transmission casing, and having a chain sprocket 57 thereon. A drive chain 58 extends forwardly from said sprocket 57 to a sprocket 59 on shaft 60 (see Figure 13). The latter shaft is suitably journaled in the front ends of the main frame members 20, 20, concentric with the axis of pivotal connection of the gathering head 11. The discharge conveyer 12 is trained about, and driven by, shaft 60, as will hereinafter more fully appear. Said shaft also has a sprocket 61 keyed near one end thereof, and engaged by a chain 62 which extends forwardly about a sprocket 63 keyed on the shaft 49a of the mat conveyer sprocket sleeve 48, previously described. The drive chains 58 and 62 may pass over the usual tensioning idler sprockets 58a and 62a, respectively.

In the preferred arrangement illustrated herein, the transmission casing 55 has one end detachably mounted on an upstanding bracket 64 disposed between the side frame plates 20, 20. The power delivery end of said casing is mounted in an aperture 55a formed in one of said side frame members and has an end flange 55b thereon which is detachably bolted to the exterior of said side frame member, as shown in detail in Figure 14. The casing also has a removable bearing member 55c for the coupling shaft 53 connected to the motor. With this arrangement,

the entire transmission casing can be bodily withdrawn laterally through the aperture 55a, after the bearing member 55c and coupling shaft 53 have been detached and the bolted connecting means to the frame has been removed.

The gathering devices 15, 15, as previously mentioned, include gathering arms 65, 65, generally of the Joy type, but in the present instance the motion of said gathering arms is modified to provide an improved arrangement and operation in conjunction with the mat conveyer 16. Said arms each include a pick or claw 66 curved at its outer end and having a plurality of teeth 67, 67 thereon. Said pick is pivotally mounted at its rear end for limited vertical movement in a socket 68 of arm 65. Said arm has pivotal connection with a crank pin 69 carried on the edge of a rotary disc 70 mounted on a gathering plate 35 at each side of the mat 16. In the form shown, the crank pin 69 is journaled in suitable bearings 69a, 69b in a bearing housing 71 on each arm 65. Each of said arms also has a rearwardly extending curved guide bar 72 which has suitable sliding engagement with a swivel pin 73 mounted on the gathering plate 35 to the rear of the adjacent disc 70. A block 73a, pivotally mounted on swivel pin 73, is slideable along a downwardly-opening guide slot 72a formed along each guide bar 72. Each of said guide bars also has an upstanding rib 74 therealong, to assist in directing the material toward and along the mat 16, as will presently appear.

The rotary discs 70 each have a depending shaft 75 journaled in suitable bearings 75a, 75b in the gear housing 42 beneath the adjacent gathering plate 35, as shown in Figure 9. Each of said rotary discs 70 also has a depending hub 76 with a bevel gear 77 thereon, meshed with the adjacent bevel pinions 50, 50 on shafts 49 and 49a. As previously described, the last named shafts are driven from motor 52 through the driving mechanism for the mat conveyer 16, so that the gathering arms are driven simultaneously with said mat conveyer.

As will be seen in Figures 1, 7 and 8, the inclined gathering plates 35 are preferably arranged at a slightly steeper angle adjacent the front of the gathering head, the change in inclination of said plates occurring along a transverse line approximately intersecting the axes of the rotary discs 70. With this arrangement, it will be observed that the rear half of each rotary plate 35 along curved lines 78, 78, so that the upper surface of said discs are substantially flush with the adjacent surface of the plate 35 to the rear of said disc, while the front edge of each disc extends at a slight angle above the adjacent surface of said plate. As will be further seen from Figure 8, the upper deck plate 40 and the mat 16 thereabove are arranged at correspondingly changed inclinations, so that the upper surface of said mat is substantially flush with the adjacent surfaces of the gathering plates 35 throughout their lengths.

It will be observed in Figure 1 that rotation of the discs 70, while the guide bars 72 of arms 65 are slidably and rockably engaged with the swivel pins 73, causes the outer ends of picks 66 to move in the irregular orbital paths indicated in dotted lines in said figure. These two paths are generally reniform or kidney-shaped and enclose what is commonly termed the "gathering area" of the arms. This general form of movement is somewhat similar to that employed with the familiar 75

Joy type gathering devices, excepting that in previous gathering devices of this kind it has been necessary that the gathering arms move in paths which overlap each other for a considerable portion of their inward and upward progress between the two discs. This has been due to the nature of previous loading head constructions wherein the elevating conveyer is disposed at a considerable distance rearwardly of the front edge of the gathering plate or shoe, and it has been necessary for the gathering arms to move the material upwardly along such plate or shoe before it can be discharged upon said elevating conveyer. It will be observed by contrast that in my novel form of gathering head, the mat conveyer 16 has a sharp wedge-like front edge or nose extending downwardly to the ground which directly engages and loads the material from along the entire central zone of the gathering head. The gathering arms 65, 65 are arranged only to engage and move the loose material inwardly in a generally transverse direction toward the opposite sides of the mat 16, so that said material will be picked up and loaded out by the latter. In other words, the paths of the gathering arms do not overlap but, instead, are spaced apart almost the full width of the conveyer 16 at their points of nearest approach. This makes it possible to spread the total gathering area of the gathering head much wider than has been possible with previous machines of this general character, so as to clear a relatively wide path for the supporting wheels of the vehicle. Moreover, it will be observed that with the changed form of movement of the arms 65, a considerably larger portion of such movement takes place well in advance and to the sides of the gathering head than heretofore, so as to increase the range and effectiveness of said gathering arms for breaking down and dislodging the coal from the working face.

It will also be observed that during the gathering action of arms 65, 65 the rearwardly extending guide bars 72, 72 with their upstanding ribs 74 are rockable across the surface of the plates 35, 35 so as to assist in moving any material that may lodge on said plates inwardly toward the mat conveyer 16.

The discharge conveyer 12 is generally of trough-like form with an endless flight type conveyer member movable therealong, consisting of a centrally disposed continuous chain 80 having a plurality of laterally extending flights 81, 81 thereon. In the form shown herein, the conveyer 12 consists of three aligned sections along 55 which the upper and lower reaches of chain 80 extend continuously. The front section 82 has upper and lower deck plates 83 and 84 rigidly mounted between the side members 20, 20 of base 10. The second conveyer section 85 has side walls 86, 86 and upper and lower deck plates 87 and 88, and is pivotally connected to a pivot rod 79 at the rear end of the front section 82, to permit vertical adjustment of the second conveyer section 85 relative to the front section 82. The third or rear conveyer section 89 is mounted for vertical adjustment with the second section 85, but an articulated connection is provided between the second and third sections to permit lateral swinging adjustment of the third section, 70 for discharging material at opposite sides of the machine, as will presently be described in detail.

The upper strand of the conveyer chain 80 moves rearwardly along the upper deck plate 83 of the front conveyer section 82 and the lower strand returns on the lower deck plate 84, as

shown in Figures 5 and 8. Said conveyer chain is driven by drive sprocket 60a keyed on shaft 60 which, as previously described, is journaled in the front ends of the side frame members 20 concentric with the pivotal axis of the gathering head 11, and is driven from the motor 52 through chain 58.

The rear conveyer section 89 has side walls 90, 90 and upper and lower deck plates 91 and 92. An idler shaft 93 is rotatably mounted at the rear end of said rear section about which the conveyer chain 80 is trained, as usual.

The articulated connection between conveyer sections 85 and 89 is of the same type shown in Arentzen Patent No. 1,785,402, but in the present instance it includes an improved arrangement for guiding the return strand of the conveyer chain, and it is also combined with an improved fluid operated elevating mechanism for the conveyer sections 85 and 89, as shown in detail in Figures 6, 15 and 16.

The rear ends of the upper and lower deck plates 87 and 88 of the conveyer section 85 are both widened and terminate along circular edges to form similar enlarged deck members 87a and 88a respectively. The two circular deck members each have coaxial pivotal connection with the corresponding deck plates of the rear conveyer section 89. In the form shown herein, the pivotal connection for the upper deck plates consists of an upright pivot pin 94 extending between the front deck plate 87a and a supporting bracket 95 secured to its under face in spaced relation therefrom, and pivotally engaged by an annular bearing ring 96 carried on the front end of a supporting plate 97 which is rigidly secured, as by welding, to the under face of the upper deck plate 91 of the rear section 89, beneath the rear end of the front deck member 87a (see Figure 16). The abutting end of the upper deck plate 91 is also widened and terminates in a concave arc concentric with the pivot pin 94, so that the upper surfaces of the upper deck plates 87 and 91 are flush with each other to afford uninterrupted movement of the conveyer chain, and the material carried thereby, in all positions of lateral swinging movement of the rear section 89.

The lower deck plates 88 and 92 are pivotally connected about an upright cylindrical jack sleeve 98 concentric with the pivot pin 94. Said jack sleeve contains a fluid operating jack device to be later described in detail. In the form shown herein, the jack sleeve 98 is formed integrally with and depends from a supporting bracket 99 connected to the lower deck plate 92 of the rear section and extends beneath the rear end of the widened lower deck portion 88a of conveyer section 85, as shown in Figure 16. A cooperating supporting bracket 100 is secured to the lower surface of the deck plate 88 of conveyer section 85, and has a depending bearing ring 101 surrounding the lower end of the cylindrical jack sleeve 98. In the form shown, the bearing ring 101 is divided on a transverse plane, with a semicircular rear half 102 having detachable flanged connection with the front half, as indicated in dotted lines in Figure 16.

With the lower deck plate arrangement disclosed, it will be observed that for simplicity and economy in construction, the upper surfaces of the rear deck plate 92 and its supporting bracket 99 are in a lower plane than the rear end of the widened front deck portion 88a, instead of having the abutting portions of said lower deck plate flush with each other, as in the case with

the upper deck plates. This difference in elevation of the lower plates is relatively unimportant, however, since the latter plates only serve to support the return strand of the conveyer chain 80, which readily rides upwardly over the rear edge of the front deck plate, as shown in Figure 16.

As will be seen from Figures 2 and 15, the side walls 86 of the conveyer section 85 are continued along opposite sides of the widened lower deck section 88a, and are flared outwardly at 105, 105. The side walls 90 of the rear section 89 are also flared outwardly at 106, 106, leaving a gap along opposite sides of both deck plates 91 and 92, between the adjacent ends of said flared side wall portions at both sides of the conveyer, to permit the desired pivotal swinging movement of said sections relative to each other. A pair of upright flexible wall members 107, 107 are also mounted above and along opposite sides of the upper deck plates 87 and 91 in longitudinal alignment with the straight portions of the side walls 86, 86 and 90, 90 of the two conveyer sections in the form shown herein, the front ends of the flexible wall members 107, 107 are rigidly connected, respectively, with the side walls 86, 86, while the rear ends are slidably engaged in overhanging guide members 108, 108 mounted on the walls 90, 90 of the rear section 89. The arrangement is such that the flexible wall members 107, 107 will flex laterally in all positions of pivotal adjustment of the rear conveyer section to form a guide for the ends of the conveyer flights 81, 81 along the upper deck plates 87 and 91 in the zone of turning movement of the latter, as shown in Figure 15.

It will especially be noted that by reason of the flared wall portions 105 and 106 along opposite sides of the lower deck plates 88 and 92, respectively, the lower or return strand of the conveyer is also guided laterally in its return movement in all positions of swinging adjustment of the rear conveyer section. When said rear conveyer is swung to its extreme position toward one side of the machine, as shown in full lines in Figure 15 (approximately 45°), the gap between the adjacent ends of the flared wall portions 105 and 106 will be entirely closed at one side of the conveyer so as to form a continuous curved guiding surface for the adjacent ends of the conveyer flights 81, which always tend to engage the side with the shorter radius. When the rear section is adjusted at any intermediate angle, as indicated in dotted lines in the same figure, the ends of the conveyer flights which bear on the flared wall portions 105 and 106, will be guided along a tangential path which is removed inwardly of the open gap between the ends of said flared wall portions. This feature constitutes an improvement over previous conveyer structures of this general character, where in no provision is made for guiding the lower or return strand of the conveyer, with the result that the ends of the conveyer flights tend to interfere with the ends of the side walls at the open gap formed therebetween, and moreover the conveyer chain has an objectionable tendency to become slack when the rear section is swung laterally. With my improved construction, the conveyer chain moves smoothly and is maintained at substantially uniform tension in all positions of the swinging rear section.

As an additional means for centering the conveyer chain 80 in its trough, centrally disposed

the upper surfaces of both deck plates of conveyer sections 82 and 85, respectively, which ribs are engaged between the side links of the chain, as shown in Figures 5 and 16. The ribs 111 on section 85 preferably terminate in advance of the turning zone between said section and the rear section, as shown in Figures 2 and 16. Similar guide ribs 112 may also be provided along the deck plates 91 and 92 of the rear conveyer section 89.

The rear section 89 is swung laterally by fluid means, herein consisting of a pair of longitudinally disposed hydraulic cylinders 115, 115 pivotally connected at their bases to opposite sides of a cross member 100a of the supporting bracket 100 beneath the conveyer section 85, and having their respective piston rods 116 pivotally connected to adjacent sides of the supporting bracket 99 of the rear section 89, as shown in Figure 15. With this arrangement, the pivoted rear section of the conveyer is preferably swung in one direction or the other by exerting rearward pressure on the proper piston rod, whereby such rearward pressure tends to counteract the normal forward stress exerted by the conveyer chain on the pivotal members 94 and 99. Thus less power is required to swing the rear conveyer section than is the case with previous constructions, in which the swinging section is actuated by pulling one or the other side of the conveyer toward the front of the machine.

A fluid jack device for bodily elevating the conveyer sections 85 and 89 is contained within the sleeve 98 which, as previously mentioned, forms the pivotal axis for the supporting bracket 99 relative to bracket 100. Said jack device includes inner and outer cylinders 118 and 119, which are mounted for telescopic movement relative to each other within the bore of the sleeve 98. The lower end of the inner cylinder 118 rests on a cross brace 113 rigidly connected between the side frame members 20, 20, as shown in Figures 6 and 16, so that the conveyer sections 85 and 89 are, in effect, fluid supported in their various positions of vertical adjustment.

The lower end of the outer jack cylinder 119 extends through a sealing ring 120 having a packing gland 121 therein and detachably connected to the lower end of the jack sleeve 98. In the form shown, said sealing ring projects beyond the lower periphery of said sleeve so as to retain the lower bearing ring 101 of the supporting bracket 100 (see Figure 16). The upper end of the outer jack cylinder has a flange 122 engaging the inner wall of the jack sleeve 98. The lower end of the inner jack cylinder 118 extends through a sealing ring 123 having a packing gland 124 therein carried on the lower end of the outer cylinder 119. The inner cylinder has a flange 125 at its upper end, engaging the inner wall of the outer cylinder. A suitable stop, herein consisting of a ring 126, is secured within the upper end of the outer cylinder for engagement by the upper end of the inner cylinder to limit upward movement of the latter in the fully collapsed position of the jack device.

Fluid pressure, as for instance oil, is introduced into the jack device through a flexible pipe 127 under control of valves, as usual. The pipe 127 communicates with the upper ends of both cylinders 118 and 119 through a vertically disposed slot 128 formed in the side wall of the sleeve 98, so that fluid pressure exerted therein will extend said cylinders any amount desired within the limits of extension afforded by both cylinders.

It will be observed that the end of the lower cylinder is slidably mounted relative to the cross brace 113, so as to readjust itself along said brace as the conveyer trough sections 85 and 89 swing vertically relative to the transverse pivot rod 79 on which said sections are hinged.

The supporting bracket 99 of the rear conveyer section 89 has an extension wing 130 connected at its rear end on a transverse pivot rod 131, and the side walls and deck plates of said rear section are divided along the vertical plane including the axis of said pivot pin, so as to permit limited downwardly tilting adjustment of the rear end of conveyer section 89, when desired. In the form shown herein, the abutting portions of side plates 90, 90 are flanged outwardly at 132, 132 and are normally connected together by bolts 133, 133. To adjust the angle of the rear end of section 89 downwardly on its pivot rod 131, the bolts 133 are temporarily removed, and shims of suitable shape and size (not shown) may be inserted between the flanges 132, 132 and the adjacent ends of the upper deck plate 91. Finally the bolts 133 are reinserted in the flanges 132, 132 to hold the two parts of the section 89 in their new relation. This tilting adjustment is often useful to accommodate the discharge end of the discharge conveyer 12 to mine cars of various heights, especially when the loading machine is operating under low roof conditions.

Referring now to details of the wheel drive and steering mechanism shown best in Figures 3 and 4, the front and rear wheels 13 and 14 on each side of the main frame 10 are driven independently by motors 135, 135 in the manner broadly disclosed in the co-pending application of Arthur L. Lee bearing Serial No. 383,329, filed March 14, 1941. Each of said motors is mounted on the outer side of its respective side frame member 20, near the rear of the main frame, and is connected through a suitable gear reduction in housing 136, and universal coupling 137 to a worm shaft 138 rotatably mounted in the rear drive gear housing 29 previously mentioned herein as parts of the mounting for the rear wheels 14 (see Figure 6). Each worm shaft 138 has a worm 139 thereon, meshed with a worm gear 140 on the shaft 28 which drives the adjacent rear wheel 14.

The front wheel 13 on the same side of the vehicle is similarly driven by a worm 141 on worm shaft 142 engaging worm gear 143 on the front shaft 24. The worm shaft 142 is connected to the rear worm shaft 138 by a connecting shaft 144 and universal coupling 145.

The steering mechanism is operated by fluid means, herein including a hydraulic cylinder 147 mounted on one of the side frame members 20 and having a piston rod 148 pivotally connected to an upright arm 149 of an L-shaped bell crank lever 150. Said bell crank lever also has a generally horizontal arm 151 and is pivoted on pin 152 carried by a supporting bracket 153 at the side of the frame member 20. A similar bell crank lever 155 having upright and horizontal arms 156 and 157 is also mounted on said supporting bracket, but in reversed or opposed relation to the bell crank lever 150, with its horizontal arm 157 pivotally and slidably engaged with the arm 151 by a pin and slot connection of well known form indicated at 158.

The upright arm 149 of the first bell crank lever 150 is connected by rod 159 to a steering arm 160 which controls the steering movement of the adjacent rear wheel 14, while the upright

arm 156 of the second bell crank lever is connected by rod 161 to steering arm 162 of the front wheel 13. The arrangement is such that any rocking movement imparted by the hydraulic piston rod 148 to bell crank lever 150 will be transmitted to the second bell crank lever 155 to rock the latter in the opposite direction, thereby causing the two wheels to be swung simultaneously at equal angles but in opposite directions, as indicated in dotted lines in Figure 3.

The front and rear wheels 13 and 14 on the opposite side of the frame are connected, respectively, with their companion front and rear wheels so as to be swung simultaneously therewith. In the preferred form shown herein, the operative connections include a compensating arrangement to provide a slight differential in pivotal movement between the two pairs of wheels. Said differential connecting devices are similar for the front pair and the rear pair of wheels, in each case consisting of a tie rod 165 pivotally connected at opposite ends to lever arms 166, 166 rigidly connected to the steering arms of the two opposite wheels. Said lever arms 166, 166, however, are each normally arranged at equal intermediate angles to the tie rod, as herein shown, at angles of approximately 45°. It will be observed that with this arrangement, when the wheels are swung to steer the vehicle toward one side, the wheel on the side toward which the vehicle is steered will be turned at a slightly greater angle than the opposite wheel. Moreover, since the two front wheels swing one way when the two rear wheels swing the other, as previously described, it will be understood that the two wheels on the inner side, i. e., the side toward which the vehicle is turned, are automatically swung at a slightly greater angle than the wheels on the outer side, thereby directing the two sets of wheels on opposite sides so that they roll along their proper arcs which, of course, are of different radii whenever the vehicle is being turned.

The various fluid actuating devices hereinbefore mentioned, including the cylinders 18, 18 for lifting and lowering the gathering head 11, the cylinders 115, 115 for swinging the rear conveyer section 89 laterally, the jack device for elevating the conveyer sections 85 and 89, and the cylinder 141 for steering all four wheels, may receive operating pressure from a pump 168, herein shown as mounted on the main frame near the transmission casing 55, and driven from the shaft of motor 52. The several valves for controlling the various fluid actuating devices named may be of any conventional form mounted in convenient position on the operator's platform 170 which, as herein shown, is disposed between the front and rear wheels at one side of the main frame. The corresponding space at the opposite side of the machine may be occupied by a box 171 containing the usual switches, controllers and electrical resistances of the usual form required for the electric motors 52 and 135, 135.

Although the various fluid actuating devices are herein described as being hydraulically operated, it will be understood that with suitable modifications they may be operated by air, if desired.

While I have herein shown and described one form in which my invention may be embodied, it will be understood that the construction thereof and the arrangement of the various parts may be altered without departing from the spirit and scope thereof. Furthermore, I do not wish to

be construed as limiting my invention to the specific embodiment illustrated, excepting as it may be limited in the appended claims.

I claim as my invention:

5 1. In a loading machine, an inclined endless elevating conveyor the lower end of which is sharply curved and adapted to have direct engagement with material substantially at ground level, and a pair of gathering devices disposed at 10 opposite sides of said conveyor and arranged for gathering movement in laterally spaced endless paths overlapping the side portion of the conveyor at its lower end and extending outwardly beyond the opposite sides of the machine and in advance of said conveyor, whereby a wide path is cleared by the machine.

15 2. In a loading machine, an inclined endless elevating conveyor the lower end of which is sharply curved and adapted to have direct engagement with material substantially at ground level, and a pair of gathering devices disposed at 20 opposite sides of said conveyor and arranged for gathering movement in laterally spaced endless paths overlapping only the lower corner portions of the conveyor and extending outwardly beyond the opposite sides of the machine and in advance of said conveyor, whereby a wide path is cleared by the machine.

25 3. In a loading machine, an inclined endless elevating conveyor, a shaft of small diameter mounted close to the ground and around which the conveyor passes in engagement therewith in a sharp curve to position the lower end of the conveyor for direct engagement with material on the ground, and a pair of gathering devices disposed at 30 opposite sides of said conveyor and arranged for gathering movement in laterally spaced paths overlapping the side portions of the conveyor at its lower end and extending outwardly beyond the opposite sides of the machine and in advance of said conveyor, whereby a wide path is cleared by the machine.

35 4. In a loading machine, an inclined endless elevating conveyor the lower end of which is sharply curved and adapted to have direct engagement with material substantially at ground level, inclined gathering plates disposed along 45 opposite sides of the conveyor with their upper surfaces in substantially the same plane as the upper surface of the conveyor, and a gathering arm mounted on each of said plates and adapted to move in an endless path overlapping only the adjacent lower corner portion of the conveyor and extending outwardly beyond the adjacent side of the machine and in advance of said conveyor.

55 5. In a loading machine, an inclined endless elevating conveyor the lower end of which is sharply curved and adapted to have direct engagement with material substantially at ground level, said conveyor being formed as a mat from a plurality of links pivotally connected together, and a pair of gathering devices disposed at 60 opposite sides of said conveyor and arranged for gathering movement in laterally spaced endless paths overlapping the side portions of the conveyor at its lower end and extending outwardly beyond the opposite sides of the machine and in advance of said conveyor, whereby a wide path is cleared by the machine.

65 6. In a loading machine, an inclined endless elevating conveyor, a shaft of small diameter mounted close to the ground and around which the conveyor passes in engagement therewith in a sharp curve to position the lower end of the

conveyor for direct engagement with material on the ground, said conveyor being formed as a mat from a plurality of links pivotally connected together, the inner surfaces of the links being provided with recesses of substantially the same radius as said shaft for receiving the peripheral portion of the shaft as they pass around it, and a pair of gathering devices disposed at opposite sides of said conveyor and arranged for gathering movement in laterally spaced endless paths overlapping the side portions of the conveyor at its lower end and extending outwardly beyond the opposite sides of the machine and in advance of said conveyor, whereby a wide path is cleared by the machine.

7. In a loading machine, an inclined endless elevating conveyor the lower end of which is sharply curved and adapted to have direct engagement with material substantially at ground level, said conveyor being formed as a mat from a plurality of U-shape links pivotally connected together with the cross piece of each link at the rear end thereof relative to its direction of travel, and a pair of gathering devices disposed at opposite sides of said conveyor and arranged for gathering movement in laterally spaced endless

paths overlapping the side portions of the conveyor at its lower end and extending outwardly beyond the opposite sides of the machine and in advance of said conveyor, whereby a wide path is cleared by the machine.

8. In a loading machine having a body and a laterally swinging extension, and an endless main conveyor extending along said body and extension and formed to turn laterally with said extension, an inclined endless elevating conveyor for feeding material to one end of said main conveyor, the elevating conveyor being formed as a mat from a plurality of links pivotally connected together, the lower end of said elevating conveyor being sharply curved and having direct engagement with material on the ground, and a pair of gathering devices disposed at opposite sides of said elevating conveyor and arranged for gathering movement in laterally spaced endless paths overlapping the side portions of the conveyor at its lower end and extending outwardly beyond the opposite sides of the machine and in advance of said elevating conveyor, whereby a wide path is cleared by the machine.

EINAR M. ARENTZEN.
